CLAUD H. FOSTER, OF CLEVELAND, OHIO.

VALVE.

No. 869,171.

Specification of Letters Patent.

Patented Oct. 22, 1907.

Application filed October 1, 1906, Serial No. 336,956.

To all whom it may concern:

Be it known that I, CLAUD H. FOSTER, a citizen of the United States, residing at Cleveland, in the county of Cuyahoga and State of Ohio, have invented a certain 5 new and useful Improvement in Valves, of which the following is a full, clear, and exact description, reference being had to the accompanying drawings.

My invention relates to valves, and more particularly to valves which are applicable as "cut-out" valves for 10 use with explosive engines to divert the exhaust directly into the atmosphere and for the operation of horns from the exhaust of an engine, especially horns of the type shown in my Patents Nos. 802,386 and 808,530, issued Oct. 24, 1905 and Dec. 26, 1905, respectively.

15 In operating valves of this type in connection with the exhaust of an explosive engine, it has been found that, unless a special construction of valve is provided, the escape of the exhaust will be impeded by the valve, producing sufficient back pressure to stop the 20 engine. Furthermore, when operating under high pressure of exhaust, either from a multi-cylinder explosive engine or from a steam engine, a valve of the flap type will, when swung across the exhaust pipe, be held there by the pressure of the fluid, making it difficult 25 to swing the valve back into position to permit the exhaust to flow through the pipe. The substitution of an ordinary three-way valve for a flap valve has been found unsatisfactory, for the reason that in the use of such valve considerable friction is produced 30 between the same and the valve casing and for the further reason that it is apt to develop sufficient back pressure to stop the engine, particularly when the engine is first started and before the engine shaft is geared up with the drive shaft.

35 The objects of my invention are the production of a valve which is capable of receiving the exhaust from explosive engines and distributing the same either to the muffler or to a pipe leading to another point of discharge without producing undue accumulation of back pressure. This other point of discharge may be directly to the atmosphere or indirectly thereto through a horn of the type above referred to.

40 A further object of the invention is the production of a valve that may be operated with a minimum of friction and that will automatically remove any deposit of carbon that may be formed within the valve casing.

45 Generally speaking, the invention may be defined as consisting of the combination of elements, for the purposes set forth, embodied in the claims hereto annexed.

50 Referring to the drawings, Figure 1 represents a view, partly in elevation and partly in section, showing a valve constructed in accordance with my invention applied to the exhaust pipe of an explosive engine, with 55 a horn applied to the pipe which receives the exhaust when the muffler is cut out; Fig. 2 represents an en-

larged sectional view of the valve and the associated parts, showing the valve in position to discharge the entire exhaust into the muffler connection; Fig. 3 represents a similar view showing the valve in position to 60 divide the exhaust between the two outlet connections; Fig. 4 represents an end elevation of the valve and its associated parts; and Fig. 5 represents a longitudinal sectional view of the valve and associated parts, taken on the line 5—5 of Fig. 2.

65 Describing the parts by reference numerals, 1 represents a tee or casing having two oppositely arranged branches 2 and 3 and a branch 4 at right angles to the length thereof. The branches 2 and 3 receive the inlet and outlet branches 5 and 6 respectively of the exhaust pipe. The latter may lead to a muffler (as indicated) where the exhaust is from an explosive engine. The branch 4 has connected thereto the pipe 7, which may lead to a horn 8. This horn is preferably of the construction shown in my Patents Nos. 802,386 and, 70 808,530, previously referred to. It has been found that, in operation, horns of this type are adapted to receive and be operated by the entire exhaust from the engine with considerably less back pressure than that produced by the muffler of the ordinary explosive 75 engine, thereby avoiding the stopping of the engine by such horns.

As will appear from the drawing, the branch 4 of the tee is located close to the outlet branch 6, whereby a narrow partition 70 is provided between the branches 80 4 and 6, for a purpose to be hereinafter described.

Within the tee is located the rotary valve 9. The body of the valve is provided with a pair of heads 10 and 10^a (see Fig. 5) the latter having a ledge 11 overlapping the body of the tee to form a seat thereon and 90 the former fitting within and having its surface substantially flush with the edge of the casing of said tee. The plate 12 is secured to the head 10, as by means of a central screw 13, a pin 14 extending through said head and plate to prevent rotation of the latter on the former. 95 The plate 12 is provided with a recess 15 at the periphery thereof, said recess terminating in shoulders 16 for engagement by a stop pin 17 projecting from the wall of the tee. The head 10^a is provided with any suitable operating means, as a lever 18, said lever being 100 secured in a boss 19 projecting from said head by means of a set screw 20.

105 The lever 18 is provided with one or more perforations 18^a adjacent the outer end thereof to permit the application thereto of the cord or cable 18^b leading to the foot lever or other operating mechanism (not shown) in the body of the vehicle.

110 The valve is provided with two ports 21 and 22 extending lengthwise thereof. Each of these ports extends from the head 10 nearly to the head 10^a, leaving a flange 23 projecting inwardly into the tee to form a bearing therewith, the inner projection of the flange being not

greater than the distance to the bore of the tee to prevent obstruction of the pressure fluid supplied to and from said tee. The port 21 is substantially 180 degrees in width, and the port 22 is considerably narrower, being 5 about 60 degrees. It is sufficiently wide, however, to enable it when in register with the outlet branch 3 to discharge the exhaust received from the inlet branch 2 without throttling. The width of the port 21 is amply sufficient to permit the port 22 to register fully with 10 the branch 4 and to register fully with the branch 3, without throttling the supply of the pipe 5 into the tee. This will be apparent from an inspection of Figs. 1 and 2, wherein the valve is shown in positions to divert all of the exhaust fluid to the horn and to the outlet branch 15 respectively. As will appear from said figures, when the valve is in position to divert all of the exhaust into the branch 4, the valve wall 25 entirely closes communication between the valve chamber and branch 3. The provision of the recess 15 and shoulders 16 in the 20 plate 14 with the stop pin 17 limits the movement of the valve in either direction by the lever 18 and prevents fluid from escaping into branch 3 when the valve is moved to its limit in the direction to supply branch 4 and from escaping into branch 4 when the valve is 25 moved to its limit in the direction to supply branch 3. By this construction, I am enabled to reduce to a minimum the bearing surface between the body of the valve and the interior of the tee and to reduce to a minimum the friction between these parts. The inwardly directed flange 23 affords sufficient bearing surface at the 30 side of the tee to prevent leakage of fluid at this point and at the same time does not materially add to the bearing surface between the valve body and the tee.

In the use of my valve with explosive engines, it has 35 been found that a considerable quantity of unconsumed carbon is deposited within the walls of the tee or valve casing. The accumulation of this carbon interferes with the operation of the valve and, to obviate the inconvenience caused thereby, I provide knife edges at opposite sides of the valve walls 24 and 25. By rotating the valve, these knife edges will remove any carbon that may be deposited on the portions of the tee or valve casing that are in their path of movement. By removing the pin 17, the valve may be given a complete 40 rotation in both directions, enabling it to remove all of the carbon that may have been deposited within the valve casing or tee. In addition to this, the valve, in its normal operation, will clean such portions of the casing as are within its range of movement.

50 As previously indicated, the lever or handle 18 is connected with the cable 18^b leading to the foot lever in the vehicle. The normal position of the valve is with the parts as shown in Fig. 2, wherein the exhaust is being discharged into the muffler. When the operator depresses the foot lever, the valve is moved to the 55 position shown in Fig. 1. To return the valve to its normal position when the operator has finished sounding the horn or operating the cut-out and has released the foot lever, I employ a spring 26, which is connected 60 with the valve body in such manner as to return the same automatically to the position shown in Fig. 2. For this purpose, the spring may be of the spiral spring type having the screw 13 extending through the body of the spiral, with one end of the spring engaging a pin 65 27 projecting from the head 14 and the other end engag-

ing or secured to the stop pin 17. A convenient manner of connecting the spring ends to said pins is to extend the same through holes in said pins.

As previously stated, the capacity of the horn 8 and its connection 7 are such as to enable the entire exhaust 0 to be supplied therethrough without the creation of such back pressure as will stop an explosive engine. Of course, no such difficulty arises when the port 22 is in register with the outlet branch. Unless the valve 75 and connections be of special construction and arrangement, however, it frequently happens that when the operator places the valve in intermediate position, whether operating the valve as a cut-out or to sound a horn, the exhaust is so throttled as to stop the engine. In my construction, however, should the valve be placed 80 in an intermediate position, as that indicated in Fig. 3, the narrowness of the partition 70 and the width of the port 22 enable a portion of the exhaust to be diverted through the connection 6 as well as through the connection 7, thereby preventing the back pressure from 85 exceeding that normally due to the muffler. The length of the recess and slot 15 is such that when one of the shoulders 16 is in engagement with the pin 17 the exhaust will be diverted entirely into the horn connection and when the other shoulder is in engagement with 90 said pin, the exhaust is diverted entirely through the outlet connection 6. In operating under high pressure of fluid, as where the valve is employed with steam under high pressure or with a large multi-cylinder explosive engine, the shape and construction of the valve 95 render it easy of operation against the pressure of the fluid, which is not the case with a gate valve.

Locating the connection 7 and branch 4 closely adjacent to the muffler connection 3 with a narrow partition 70 therebetween enables me to lessen the width of the port 22 as well as the range of movement of the valve. This permits of a reduction of the metal in said valve to a minimum, with a corresponding reduction of friction between the same and the interior of the tee or valve casing. Moreover, the shape of the valve 100 105 materially contributes to the avoidance of back pressure, being preferably cylindrical in shape with a concave interior, whereby the exhaust admitted into the valve body through the inlet branch of the exhaust pipe is deflected readily and with comparatively little friction into either of the outlet branches of the casing or tee. 110

I claim:

1. The combination, with the exhaust pipe of an explosive engine, of a valve casting or tee in said pipe, and a rotary valve body in said tee or casing having an inlet port and an outlet port, the wall of said valve body being provided with cutting edges adjacent said ports, and a removable stop for limiting the rotation of said body, substantially, as specified. 115
2. The combination, with a fluid supply pipe, of a rotary valve body therein having an outlet port, the wall of the valve body adjacent said port being provided with a cutting edge, means for rotating said valve, and a removable stop for limiting such rotation, substantially as specified. 120
3. The combination, with a fluid supply pipe, of a rotary valve therein comprising a casing and a hollow valve body having one or more ports, said valve body being provided with a cutting edge, means for rotating said body, and a removable stop for limiting such rotation, substantially as specified. 125
4. The combination of a main fluid supply pipe, a branch pipe connected thereto, and a rotary valve at the junction of said pipes, said valve comprising a casing and a valve body having therein two ports, one of said ports 130

- being substantially 180 degrees in width and the other being of sufficient width to register with the branch pipe connection and the exhaust branch of the supply pipe, the interior of said valve body being substantially cylindrical, substantially as specified.
5. A valve for exhaust pipes of automobiles and the like, said valve comprising a cylindrical casing having an inlet connection and a pair of outlet connections, a rotary cylindrical valve body in said casing, said valve body having two ports extending substantially the length thereof, one of said ports being substantially 180 degrees in width and the other being of a width to register fully with either of the outlet connections, heads closing the ends of the valve body, one of said heads engaging the outer surface of the casing and having a flange projecting inwardly therefrom and fitting the valve casing, said flange terminating short of the bore of the inlet connection, substantially as specified.
6. A valve for exhaust pipes of automobiles and the like, 20 said valve comprising a cylindrical casing having an inlet connection and a pair of outlet connections, a rotary valve body in said casing, said valve body having ports extending substantially the length thereof, one of said ports being substantially 180 degrees in width and the other being 25 of a width to register fully with either of the outlet connections, heads closing the ends of the valve body, and a flange projecting inwardly from one of said heads into each of said ports and fitting the valve casing, said flange terminating short of the bores of the valve casing connections, substantially as specified.
7. The combination with a fluid supply pipe, of a tee or casing having an inlet branch and a pair of outlet branches, said outlet branches being separated by a narrow partition, a cylindrical rotary valve body in said tee or 35 casing, a horn connected with one of said outlet branches, said valve body having a port substantially 180 degrees in width and a port opposite the former port and of sufficient width to register with either or both of the exhaust connections, and means for rotating said valve, substantially as specified.
8. The combination of a tee or casing having a valve seat therein and provided with an inlet connection and a pair of outlet connections, a valve in said tee or casing having a wide inlet port and a single outlet port adapted 45 to communicate with either of said outlet connections, means for rotating said valve in one direction, means connected with said valve and adapted to rotate the same in the opposite direction, and stop mechanism arranged to limit the rotation of the valve in either direction, substantially as specified.
9. The combination of a tee or casing having a valve seat therein provided with an inlet connection and a pair of outlet connections, a rotary valve body therein having an inlet port and an outlet port adapted to register with either of the outlet connections, said valve body having at 55 one end a head provided with stop shoulders, a pin carried by said casing and projecting between said shoulders, a spring support carried by the central portion of said head, a spring on said support and having one end engaging said pin, a second pin projecting from said head and engaged by the other end of said spring, and means for rotating said valve against the action of said spring, substantially as specified.
10. The combination of a tee or casing having a valve seat therein provided with an inlet connection and a pair of outlet connections, a rotary valve body therein having an inlet port and an outlet port adapted to register with either of the outlet connections, means for rotating said valve in one direction, a pin on the casing, stops carried 65 by the valve body for limiting the movement of said valve in either direction, and a spring connected with said valve and engaging said pin for rotating the valve in the opposite direction from the rotating means, substantially as specified.
11. The combination, with the exhaust pipe of an explosive engine, of a branch pipe connected thereto, and a valve at the junction of said pipes, said valve comprising a casing having an inlet port and an outlet port adapted to discharge fluid into the branch pipe, and a rotary hollow valve body in said casing having a port for the reception 75 of fluid from the exhaust pipe and an outlet port, the wall of said body adjacent said outlet port being provided with a cutting edge, substantially as specified.
12. The combination of a main fluid pipe, of a branch pipe connected thereto, and a rotary valve at the junction 80 of said pipes, said valve having therein two ports, said ports being so proportioned and arranged relatively to said pipes that one of them may be in continuous communication with the inlet side of the main pipe while the other is in position to divert the fluid into either the branch pipe, the outlet side of the main pipe, or into both, without materially impeding the flow of the fluid through said valve, substantially as specified.
13. The combination of a tee having a valve seat therein, an engine exhaust pipe comprising an inlet branch 95 and two outlet branches communicating with said tee, a rotary valve body in said tee, said valve body having two ports therein, said ports being so proportioned and located with reference to the inlet and outlet branches that one of said ports may be in continuous communication with the 100 inlet branch while the other port is in communication with either, or both, of the outlet branches, and means for rotating said valve, substantially as specified.
14. The combination of a tee having oppositely arranged inlet and outlet connections and an intermediate 105 branch connection adjacent said outlet connection with a narrow partition therebetween, a valve body in said tee having two ports therein, said ports being so located and proportioned that one of them is in continuous communication with the inlet connection while the other is in 110 communication with the branch connection the outlet connection, or both, and means whereby said valve may be rotated, substantially as specified.
15. The combination with the exhaust pipe of an engine, of a tee in said pipe, said tee having connections for 115 the inlet and outlet portions of such pipe and a connection intermediate of said former connections, a rotary valve in said tee, said valve having two ports therein, said ports being so proportioned and arranged that one of them will be in continuous communication with the inlet connection 120 of the tee while the other is in communication with either the outlet connection, the intermediate connection, or both, and means for limiting the movement of said valve to prevent the latter port from being moved to any other position than to communicate with either or both of its connections, 125 substantially as specified.
16. The combination of a tee having a valve seat therein and having oppositely arranged inlet and outlet connections for fluid and a branch connection intermediate of said first-mentioned connections, a rotary valve within 130 said tee having at one end a plate engaging the casing of the tee, said plate having a slot therein, a pin projecting from said casing into said slot, said valve being provided with two ports, the relative sizes and arrangement of such ports and slot being such that when the pin is in engagement with the plate at one end of the slot, one of said ports is in communication with the outlet connection of the tee, and when the pin is in engagement with the slot at the other end of the plate said port is in communication with the intermediate connection, the other port being in 135 communication with the inlet connection for both positions of the former port, substantially as specified.

In testimony whereof, I hereunto affix my signature in the presence of two witnesses.
